T. E. BATTERSON, OF ROCHESTER, NEW YORK.

Letters Patent No. 77,570, dated May 5, 1868.

IMPROVED FRUIT-JAR.

The Schedule referred to in these Letters Patent and making part of the same.

TO ALL WHOM IT MAY CONCERN:

Be it known that I, T. E. BATTERSON, of Rochester, in the county of Monroe, and State of New York, have invented a certain new and useful Improvement in Fruit-Jars; and I do hereby declare that the following is a full and exact description thereof, reference being had to the accompanying drawings, making part of this specification.

Figure 1 is a perspective view of the top of a jar showing my improvement.

Figure 2, a vertical section.

Like letters of reference indicate corresponding parts in both figures.

My invention consists in combining loosely with the cover of the jar, a wire clamp, capable of end motion, so as to adapt to the holding-lugs if the cover is not placed on centrally, and also having a central coil to allow a degree of spring.

In the drawings, A indicates a jar, of ordinary form, and B a cover, fitting thereon, with packing-ring a between. The cover itself has nothing peculiar, except that the edge, b, is turned down, in a flaring manner, to hug closely to the packing, and produce a broad bearing.

The top of the cover has ears or bearings, c c, in which rests loosely a wire clamp, C, so as to move freely endwise. The ends, d d, of the clamp turn down to engage with lugs f f of the jar, and a coil or turn, g, is made in the centre to produce a degree of elasticity or spring. If desired, the coil, g, may be dispensed with.

The great advantage in this invention is the free movement of the clamp in the bearings c c, and the employment of the spring-coil g.

By the free movement I accomplish two advantages: First, the turning of the clamp upon its axis allows the ends, d d, to strike under the lugs f f, without the turning of the cover itself, as where the clamp is soldered fast to the cover; I therefore avoid both displacement and cutting of the packing-ring, as where the cover is turned. Second, if the cover is not centrally applied on the jar, the free action allows the clamp to move endwise to engage properly with the lugs.

The employment of the coil gives the requisite elasticity or spring to the clamp in engaging with the lugs, and it also serves as a handle by which to turn the clamp down and up.

I am aware that a wire clamp has been soldered fast to the cover; such I do not claim.

What I claim as my invention, and desire to secure by Letters Patent, is

The combination, with the cover B, of the wire clamp C, resting loosely in bearings c, so as to have a free turning and longitudinal movement, the whole arranged as described, and operating in the manner and for the purpose specified.

In witness whereof, I have hereunto signed my name in the presence of two subscribing witnesses.
